UNITED STATES PATENT OFFICE

RUDOLPH W. MILLER, OF BROOKLYN, NEW YORK

ORNAMENTAL FOUNTAIN

Application filed August 21, 1931. Serial No. 558,429.

This invention relates to display devices, such as ornamental fountains or the like, and an object of the invention is to provide a device of this type constructed and arranged to have novel and attractive features which render it particularly adapted to places of public or semi-public gathering.

One embodiment of the invention is illustrated in the accompanying drawing which is 10 a sectional diagrammatic view of a preferred construction, although it will be apparent that numerous modifications can be made therein.

The particular embodiment of this invention which has been chosen for the purpose of illustration, includes a fountain having a radio outlet associated therewith, the whole being provided with ornamental and eye-arresting features. The fountain includes a 20 basin 5 having a water nozzle or outlet 6 and a sound or radio outlet 7 associated therewith. As illustrated, the water and sound outlets are mounted upon a suitable support 8 of any desired type or form, such as the 25 figure illustrated, which in turn is mounted on a rotatable pedestal 9 located above the center of the basin 5. The supporting structure for the rotating pedestal 9 is concealed within a hollow tube 10 in the basin below 30 the normal water level. A water chamber 11 is located below the basin 5 and a water tube 12 extends upwardly therefrom to a suitably supported hollow casting 13 connected to the top of the water tube and having a laterally disposed water outlet 14 at one side thereof. A flexible copper tube or the like 15 extends from the water outlet 14 upwardly through a hollow supporting member 16 upon which the pedestal 9 is mounted. 35 The copper water tube 15 extends through the interior of the support 8 to the water outlet or nozzle 6. Sound is conveyed to the ornamental horn 7 or other sound outlet from a sound-conveying tube 17 connected at one 40 end with a source of sound, such as a loud-speaker diaphragm or the like, by means of a sound tube and conduit 18 extending upwardly through the water chamber 11 and through the water tube 12 to the casting 13 45 where it is connected to a copper tube 19 ex-

tending upwardly from the sound passage 20 in the casting through the supporting member 16, pedestal 9 and figure 8 to the sound outlet 7. For simplicity of illustration, I have illustrated the sound outlet 7 as 55 an ornamental horn to which sound is conveyed through the connections described. However, it will be apparent that the horn 7 can be a suitable radio loud-speaker actuated from any desired source (not shown), the 60 wiring connections to the speaker extending upwardly through the conduit 18, tube 16, etc.

The ornamental figure 8 is adapted to be rotated, and for this purpose a gear 21 is 65 secured to the water tube 12 above the water chamber 11 and driven by a chain 22 connected to a gear 23 which is in turn operated from a suitable transmission 24. The tube 12, the casting 13 and associated parts are 70 supported for rotation, and the hollow pedestal supporting tube 16 extends upwardly through a suitable packing 25 provided at the bottom of the fountain basin 5. The conduit 18 being secured to the casting 13 rotates therewith, a packing 26 at the bottom 75 of the water chamber 11 and a similar packing 27 at the union 28 which connects the tube 17 and conduit 18, permitting such rotation. A water pump 29 draws water from the basin 80 through a connection 30 and delivers it to the water chamber 11 through a suitable pipe 31, providing for circulation of the water without requiring any outside connections. A suitable source of power such as the motor 85 32 drives the pump 29 and also drives the transmission 24 through a suitable gear-reduction box 33. The basin 5 is provided with a compartment 34 for variously colored electric lights 35 connected to the usual circuits 36 which are controlled by a rotary three-way switch 37 of standard construction. The switch is slowly operated from the transmission 24 by a suitable chain 38 or the like. 90

It will be apparent that operation of the motor 32 will cause the pump to circulate water from the basin 5 through the water chamber 11, tube 12 and connecting pipe 15 to the water outlet or nozzle 6. At the same time, 95

the motor will rotate the supporting mechanism for the figure 8 and the latter will slowly rotate above the fountain. Sound, radio programs or the like, can be provided 5 through the horn or sound outlet 7, either by connecting the outlet through the tubes 17, 18 and 19 with the diaphragm of a loud-speaker, or else providing a loud-speaker at the point 7 and running the connecting wires 10 through the tube 17 and conduits 18 and 19. Operation of the gear-reduction box 33 and the connected transmission 24 not only rotates the figure 8, but causes operation of the light-controlling switch 37 so as to cause the 15 lights 35 to play upon the fountain and figure with constantly changing colors.

I claim as my invention:

1. An article of manufacture having in combination separate sound and water outlets, a support therefor, a conduit associated with said sound outlet, a water pipe connected to said water outlet and concealed within said support and means for rotating said support. 20

2. An article of manufacture having in combination a water basin, a water nozzle, a sound outlet, a concealed water supply pipe leading to said nozzle, a water chamber connected to said pipe and a conduit extending through said chamber and leading to said outlet. 25

3. An article of manufacture having in combination a water basin, a water nozzle, a sound outlet, a rotatable support therefor including a hollow tube extending downwardly through said basin, means for rotating said support, a water supply connection extending through said tube to said nozzle and a conduit associated with said outlet. 35

4. An article of manufacture having in combination a water basin, a water nozzle, a sound outlet, a rotatable support therefor including a hollow tube extending downwardly through said basin, means for concealing 40 said tube, means for rotating said support, a water supply connection extending through said tube to said nozzle and a conduit extending through said tube associated with said outlet. 45

5. An article of manufacture having in combination a water basin, a water nozzle, a sound outlet, a rotatable support therefor including a hollow tube extending downwardly through said basin, means for rotating 50 said support, a water supply line extending through said tube to said nozzle, a stationary water chamber, a flexible connection between said water chamber and said water supply line to permit movement of said

6. An article of manufacture having in combination separate sound and water outlets, a rotary support therefor, a water basin 55

associated therewith for collecting water discharged from said water outlet, a lighting mechanism arranged to illuminate such support, a control switch for said mechanism and means for simultaneously rotating said support and operating said switch in co-ordinated relationship. 70

7. An article of manufacture having in combination separate sound and water outlets, a support therefor, connections to said sound outlet, a water pipe connected to said water outlet, said connections being concealed in said support, means for rotating said support, means for illuminating said support, and means for operating said illuminating means simultaneously with the rotation of such support. 75

8. An article of manufacture having in combination separate sound and water outlets, a support therefor, a conduit leading to said sound outlet through said support, a water pipe connected to said water outlet and concealed within said support, a water basin for collecting water discharged from said water outlet and means for circulating water 80 from said basin through said pipe and outlet. 90

9. An article of manufacture having in combination separate sound and water outlets, a support therefor, connections to said sound outlet, a water pipe connected to said water outlet, said connections being concealed in said support, means for illuminating said support, a water basin, means for circulating water from said basin through said water outlet and means for operating said illuminating means simultaneously with said water 95 circulating means. 100

In testimony whereof, I have signed my name to this specification this 20th day of August, 1931. 105

RUDOLPH W. MILLER.
